UNITED STATES PATENT OFFICE.

GEORGE H. PERKINS, OF PHILADELPHIA, PENNSYLVANIA.

MACHINE FOR SHEARING SHEET METAL.

SPECIFICATION forming part of Letters Patent No. 276,625, dated May 1, 1883.

Application filed November 3, 1882. (No model.)

To all whom it may concern:

Be it known that I, GEORGE H. PERKINS, of the city and county of Philadelphia, in the State of Pennsylvania, have invented an Improvement in Machines for Cutting, Shearing, or Trimming Sheet Metal, of which the following is a specification.

This invention is an improvement upon an apparatus for cutting or shearing sheet metal which was invented by me and patented to me, as assignor to the Le Comte & Perkins Manufacturing Company, (Limited,) in and by Letters Patent of the United States No. 194,168, dated August 14, 1877; and it is also an improvement upon an apparatus of the same class invented by me and patented to me in and by Letters Patent of the United States No. 260,779, dated July 11, 1882.

To the above-named Letters Patent reference is to be made for a thorough understanding of my present improvements, as the latter relate to, employ, or are connected with the principal instrumentalities of my former invention.

My invention relates to a class of devices which are employed to trim the edges of sheets of tinned iron and other sheet metal, and in which the trimming is accomplished in a right line, an edge-strip being cut from the sheet in order to reduce its width or length, according to the position in which it is introduced into the machine.

My present invention embraces means for more accurately feeding or supplying the sheets to the cutting mechanism, for controlling and guiding the metal in such introduction, for preventing its displacement from rectilinear position upon the feeding-chute, and for preventing the buckling of the sheet upon the chute.

It also embraces improved means for retaining the sheet upon the chute until the moment of its final passage to the cutting mechanism.

In my first patented apparatus the principle of operation of trimming the sheet of metal is carried into effect by means of certain combined instrumentalities, which may be briefly stated to consist of an endless belt or carrying-apron, which is caused to travel against and around a revolving bending-drum provided with a circular cutting-edge, operating in connection with another circular cutter upon a drum or shaft contiguous to the bending-drum,

the apron being held taut against the drum, which it semi-encircles by means of tightening-rolls, and of a feeding-chute whose feeding extremity is disposed in such relation to the drum over which the apron is bent that sheets of metal fed upon the chute descend upon the drum beneath the point where the apron first comes into tangential contact therewith, so that the sheet is gripped between them and carried half-way around the drum in such manner that its edge in the passage comes between the cutting-edge of the bending-drum and the cutter which operates therewith, and is thereby trimmed, the trimmed sheet being discharged at the rear of the bending-drum. All of the above members are suitably assembled in the frame-work.

In my second patented invention above cited certain improvements upon my first patented invention are embraced, which it is proper briefly to mention here, for the reason that my present invention embraces in part further improvements upon said last-named patented invention. Briefly stated, my second patented invention cited embraces the application to the chute or feeding-table of pushers adapted to project the sheet metal fed upon said chute into contact with the cutting mechanism. It also embraces the combination, with mechanism for shearing a strip from the edge of a sheet, of two chutes located in different planes, (the first adapted to receive a sheet of tin supplied to the machine and feed it upon the second chute, and the second chute adapted to receive the sheet so fed.) It also embraces, in combination with the two chutes referred to, mechanism for advancing the sheet after it has descended upon the second chute in contact with the shearing mechanism. It also embraces the combination, with the main chute, of a spring-plate applied to one side of the chute and adapted by suitable mechanism to set over the sheet true against the opposite side of the chute; and it also embraces the combination of said primary and secondary chutes, each of which is provided with a gate controlling its discharging end. Other minor combinations and instrumentalities are embraced, which are not improved upon in my present invention, and which therefore do not require mention.

The elements of my second patented inven-

tion which I have above referred to are herein improved upon, but, except in their improved form and relation, are not claimed in this application.

- 5 In the accompanying drawings I have represented an apparatus conveniently embodying my improvements. Figure 1 depicts in right-hand side elevation a cutting and shearing apparatus conveniently embodying my improvements. Fig. 2 is a view similar to Fig. 1, with the exception that the right-hand side frame, or that nearest the eye, and all members of the apparatus exterior to said right-hand side frame are removed; while the main chute and primary chute are represented in central sectional elevation. In this view the apparatus is represented at the moment when the sheet of tin has descended from the primary chute upon the main chute and before the 10 pushers have operated to force it down the chute and into the embrace of the bending-drum, during the period, also, when the hold-downs are bearing upon the sheet and at the moment when the main gate is closed to prevent the passage of the sheet of tin fed upon it. Fig. 3 is a partial detailed view similar to that of Fig. 2 of certain of the parts represented in said Fig. 2, especially illustrative of the operation of the pushers, main gate, hold-downs, and stop-levers, the various members of the apparatus being represented at the moment when the sheet of tin is in the act of descending from the primary chute upon the secondary chute, before the pushers have been 15 retracted after their last forward throw, and at the time when the stop-levers block the passage of the sheet from the main chute. Fig. 4 is a top plan view of the apparatus represented in the previous views, the view being 20 taken at right angles to the plane of the main chute and in the direction of the arrow No. 1 in Fig. 2, and the apron-roll E being supposed removed. Fig. 5 is a rear elevational view of the apparatus represented in the previous views, 25 taken in a plane at right angles to the plane of the main chute and in the direction of the arrow No. 2 of said Fig. 2. In this view sight is taken down the main chutes and the parts are in the position which they are represented 30 as occupying in Fig. 2. Fig. 6 is a sectional detailed elevation taken transversely across the lower portion of the main chute at a point in advance of the gage-plates and at right angles to said chute, the plane of view being 35 similar to that of Fig. 5. Fig. 7 is a sectional detail view transversely to one of the tubular bearings of the gage-plates, sight being taken at right angles to the plane of the section of Fig. 6 on the line 3 3 of said Fig. 6. Fig. 8 is 40 a side elevational detail of one of the pushers. Fig. 9 is a sectional detail representing a convenient method of securing the cutters m^x to one of the side frames. Figs. 10 and 11 are top plan views of the primary and main chutes, 45 illustrating two positions of a sheet of tin, t^x , upon the main chute, in Fig. 10 prior to its being acted upon by the pushers, and in Fig. 11

at the moment when the pushers are forcing it down the main chute, representing also the positions of the gage-plates with respect to 70 the above positions of the sheet. Fig. 12 is a view in perspective of a sheet of tin which is, for illustration, supposed removed from the machine after the action of trimming its edges has been commenced.

75 Similar letters of reference indicate corresponding parts.

In the accompanying drawings, A represents the side frames of the machine, which are two parallel housings of suitable material 80 suitably erected and united together by cross-bars B or other suitable means. These frames are of semicircular contour, cut out preferably in V shape from the upper edge down to an approximately central point in order to afford a convenient central bearing, C, for the shaft of the bending-drum D, which is placed horizontally between the side frames, as well represented in Figs. 1 and 2.

E E^x are apron-rolls likewise transversely and horizontally journaled between the side frames in such position and relation as to cause the endless apron F, which travels around them, to semi-encircle the bending-drum and be stretched taut against it, as represented in 95 Fig. 2. The two lower apron-rolls are adjustable to impart the requisite tension to the apron, as described in my first patent.

G, Figs. 1 and 2, represent bosses in the frame-work, designed to receive revolving cutters of the character patented to me in and by Letters Patent No. 240,176, dated April 12, 1881, which operate upon the sheet of tin bent around the drum and serve to trim its edge.

100 In Fig. 9 are shown two cutters, m^x m^x , secured in said bosses G in the housings, and so placed relatively to the bending-drum D as to operate upon the edge of a sheet of metal caused to pass around said drum.

105 H is the main or feeding chute, being an inclined platform erected at an angle of forty-five degrees between the side frames of the machine, and having its lower or discharging end terminated upon the surface of the bending-drum at a point in advance of the point at 110 which the apron encounters said bending-drum, as represented in Figs. 1, 2, 3, and 4. The chute is provided with sides I, which extend upwardly and backwardly beyond the receiving end J of the floor of the main chute.

115 All of the foregoing elements—the cutters, however, being of a different character—were embodied by me in the invention for which the first Letters Patent hereinbefore referred to were granted to me.

120 K is the primary chute, erected between the sides I of the main chute at a point above the receiving end of the latter. It is designed to afford the first resting-place in the machine for the sheet to be trimmed. This primary chute is controlled as to its discharging extremity by a main gate, L, supported transversely between the sides of the chute upon an axial rod, M, which is actuated either to

rise and permit the descent by gravity of the sheet upon the main chute, as represented in Fig. 3, or else to block the discharging end of the primary chute and retain the sheet thereupon. The primary chute and main gate constitute a part of my second patented invention.

The several devices which, either separately or in combination with the elements just described, constitute the subject-matter of my present invention are those hereinafter described and claimed.

N is a driving-shaft which is suitably set in the rear of the frame-work, and is operated from a pulley, O, or kindred driving device, and which is equipped with a series of cams which separately or in conjoint operation impart movement to all of the operative parts of my machine. Erected upon this shaft is a main eccentric, P, the periphery of which is grooved so as to receive and retain against lateral displacement a circular yoke, Q, fitted thereupon.

R is a rock-shaft suitably journaled in the frame-work transversely thereto and to the rear of the cam-shaft.

S is a rock-shaft arm erected upon the rock-shaft, and designed, through an adjustable pitman, T, to impart motion to the pusher-frame.

The rock-shaft arm is operated to its oscillatory throw by virtue of its connection through the adjusting-plate U with a yoke-arm upwardly projecting from and being a part of the circular yoke Q of the main eccentric. Through the above means, upon the revolution of the cam-shaft, oscillation is imparted to the rock-shaft.

V, Figs. 2, 3, and 5, is a pusher-frame, being a sliding cross-head adapted to travel lengthwise of the main chute by means of a dovetailed projection, W, fitted within a dovetailed longitudinal way, X, Figs. 2 and 4, extending centrally lengthwise of the main chute and channeled in the same.

Y is a stirrup, Figs. 1, 2, and 5, secured against the under face of the dovetailed projection W, and projecting downwardly through the way X in the main chute. To this stirrup is connected the forward extremity of the pitman T, which is pivoted to the upper extremity of the rock-shaft arm. Upon the oscillation of the rock-shaft arm through the above-described connection the pusher-frame is caused to reciprocate lengthwise of the main chute.

Z are two parallel grooves or ways channeled out of the upper or bearing surface of the main chute at either side and lengthwise thereof. They can be seen in Figs. 4 and 5. In these grooves play carriers a, Figs. 5 and 8, fitted thereto and connected with the under face of the pusher-frame, so as to be operated thereby. The proportions of the carrier are such that they are embedded in the grooves Z, and do not project above the plane of the face of the main chute.

b, Figs. 2 and 8, are jaws adjustably erected upon the carriers, and c are the guards of the

same. The carriers, jaws, and guards together form the pushers. I derive from this construction of the pushers steadiness of throw and a fixed and invariable relationship between the two pushers which is of advantage in the exact advance of the sheet.

d, Figs. 2, 3, and 4, are feet upon the main gate, well made when of the form represented in the drawings—that is to say, with a broad bearing-reach upon the main chute. The feet rise and fall with the main gate, which is operated from a cam, e, Figs. 1, 4, and 5, located upon the cam-shaft exterior to one of the side frames, and adapted to bear upon the rear extremity of a lever of the first order, f, Fig. 1, the front extremity of which is connected with the lower extremity of the links g, the upper extremity of which is connected with a crank, h, upon the axial rod M of the main gate. The depression of the lever in the revolution of its cam upon the cam-shaft causes the elevation at predetermined intervals of the main gate.

i, Figs. 1 and 4, are springs applied on either side of the chute to the axial rod M in order to return the gate to its closed position after the lever-and-link connection thereof have been relieved of the depressing influence of the cam e in the revolution of the shaft.

j, Figs. 2, 3, and 4, are hold-downs, being long arms loosely hung at their rear ends upon the axial rod of the main gate, first curved downwardly as to a part of their extent, and thence continued in straight lines so as to constitute extended pressing-surfaces parallel with the main chute, and adapted under suitable influences, hereinafter described, to press at stated intervals thereupon, and retain the sheet firmly against said chute and prevent its buckling during the time when it is being pushed down the latter by the pushers. The movement of these hold-downs above referred to is occasioned by the rocking of a secondary rock-shaft, k, Figs. 1, 2, and 4, transversely journaled with respect to the main chute, and overhanging the same, to which the hold-downs are connected by links l, Fig. 2, attached to rock-shaft arms m, keyed upon said rock-shaft.

Motion of oscillation is imparted to said secondary rock-shaft by means of a bell-crank lever, n, Fig. 1, pivoted against the side of the frame-work, linked as to its upper arm by means of the link o to a crank on the end of the secondary rock-shaft, and operated as to its horizontal arm by means of a lifting-cam, p, upon the right-hand extremity of the driving-shaft. The operation of this cam is so timed as to deflect the bell-crank and thence rock the secondary rock-shaft, so as to raise the hold-downs from the chute at the moment when the sheet of tin has been completely entered into the embrace of the apron and bending-drum, and is also so timed as to enable the proper return of the hold-downs through the influence of a spiral spring, q, Fig. 1, linked to the horizontal arm of the bell-crank, and operating to draw the latter downward upon the revolution of the cam from beneath said horizontal arm.

are two stop-levers, Figs. 1, 2, 3, 4, 5, and 6, fulcrumed to the under face of the main chute, and provided as to their front extremities with upturned toes, which project through 5 openings *t*, Fig. 4, in the main chute, close to its discharging end. The rearwardly-extending arms of these stop-levers rest upon lifting-cams *u*, Figs. 2 and 5, keyed upon the cam-shaft, and operating upon their lift to elevate 10 said rearwardly-extending extremities of the levers. In that position of the driving-shaft in which the cams referred to do not operate to elevate the stop-levers, said levers occupy the position represented in Fig. 3—that is to 15 say, with their toes extending through the slots in the chute which receive them, and serving to block the discharging extremity of said main chute. In the revolution of the driving-shaft at the moment when the cams *u* lift 20 these levers the toes are withdrawn from the slots and no longer block the chute, but permit the descent of the sheet therefrom, as represented in Fig. 2.

v, Fig. 2, are spiral springs, which serve to 25 return the stop-levers after the lift of their cams, and which also operate to keep them constantly in engagement with said cams. These cams are so timed as to cause the operation of the stop-levers oppositely with the 30 operation of the pushers—that is to say, before the pushers advance the toes of the stop-levers are retracted, and upon the retraction of the pushers the toes of the stop-levers are advanced.

35 *w* are spring presser-feet, pivoted upon a cross-bar, *x*, erected above the chute transversely thereto, and near its discharging end. They are represented in Figs. 1, 2, 3, 4, and 10 of the drawings, and they serve to prevent the 40 buckling of the sheet at the moment of its discharge to the carrying-apron, and also its possible escape from arrest by the toes of the stop-levers.

45 *y* are supplemental presser-feet, of elastic material, which combine with the spring-presser-feet referred to, and are applied for similar reasons.

In my second patented invention cited I have described a spring presser-plate applied 50 to the inside face of one side of the main chute and adapted to force the sheet of tin over against the opposite side of the chute, which is stationary. I have now contrived another means for effecting this adjustment of the sheet, 55 which is as follows: *z*, Figs. 1, 2, 3, 4, 6, 10, and 11, are gage-plates, being in effect adjustable portions of the sides of the main chute. They are, considered with regard to the plane 60 of the main chute, vertical plates curved downwardly along their uppermost vertical edges, and which are supported upon the inner extremities of slides *a*^x, Figs. 1, 4, 5, 7, 10, and 11, passing through tubular slide-bearings *b*^x, and also passing through other bearings *c*^x, exterior thereto. Around the right-hand slide, and between its exterior bearing, *c*^x, and the 65 collar *d*^x thereupon, Figs. 4, 6, 10, and 11, is a

compressed spiral spring, *e*^x, which, in the absence of opposing instrumentality, operates to throw the right-hand gage-plate in. *f*^x is a similar spiral spring surrounding the left-hand slide, and between the tubular bearing *b*^x thereof and the collar *g*^x thereupon. This spring, in the absence of opposing force, operates to throw out the left-hand side gage-plate. *h*^x, 70 Figs. 6 and 7, are slide-studs downwardly projecting from the slides referred to, rigidly connected therewith, for convenience incased with in the tubular bearings of said slides, and passing through slots transversely cut in the main 75 chute, as represented in Figs. 6 and 7. These studs are embraced as to their lower portions, which project below the under face of the main chute, by the forked ends of slide-operating levers *i*^x *j*^x, Figs. 1, 2, 5, and 7, which are suitably 80 pivoted beneath the main chute in such manner as to be capable of being vibrated from side to side. The opposite or rear extremities of these levers are provided with laterally-facing 85 heels *k*^x, each of which faces in the same direction, and which bear respectively against cams *l*^x, Fig. 5, the operating-surfaces of 90 which are upon their sides and not upon their peripheries. These cams *l*^x are so formed as to occasion the lateral throw of the slide-operating levers, from which throw results the lateral 95 throw of the slides which carry the gage-plates. These cams *l*^x are so timed as to throw the slide-operating levers at intervals which are 100 not correspondent as to both levers, but are 100 such as to occasion the deflection of the left-hand gage-plate inwardly by its lever before the deflection of the right-hand gage-plate inwardly by the expansion of the spring which is coiled about its slide. The operation of 105 these slide-operating levers is opposite, the left-hand lever positively operating to throw in the left-hand gage-plate, while the right-hand lever positively operates to draw out the right-hand gage-plate. This arrangement of 110 coarse renders the operation of the spiral springs opposite, the left-hand spring operating to draw out the left-hand gage-plate and the right-hand spring operating to throw in the right-hand gage-plate. This arrangement 115 may of course be modified, as any skillful mechanician will at once comprehend. Be the operation, however, that illustrated and explained, or of other character, the gist of the contrivance resides in the movement of the gage- 120 plates alternately—that is to say, in the placing and retaining first of the left-hand gage-plate slightly inside the line of the left-hand side of the main chute, of which it is in effect a part, and while it is so held in moving the 125 right-hand gage-plate inwardly, so as to cause it to set the sheet up and over against the other plate, which is still in, and in then causing the receding of first the right-hand plate and then the left. The object of this alternate 130 and opposite action of the gage-plates is to enable the accurate lateral setting of the sheet upon the main chute—that is to say, its set with respect to the sides of said chute and its

placing in the proper position with respect to the line of the cutters, so that when the pushers descend they may encounter the sheet in proper position for them to push it into the cutters, in order that the latter may trim so much of the edges only as is desired. The receding of both the gages prior to the operation of the pushers and after the completion of their proper function avoids all frictional resistance against the sides of the sheet in its descent, as the sheet is narrower than the full breadth of chute, and as the side gages are, as described, withdrawn from contact with it prior to its descent. The necessity of withdrawing both gage-plates prior to the descent of the sheet arises from the fact that if one gage-plate were allowed to remain in and in contact with the sheet, and the side of the sheet so in contact should happen to be other than right angular with respect to the end of the sheet against which the pushers act, the tendency of the gage-plate would be to cause the side of the sheet to true itself with said gage-plate, throw the end the pushers operate upon out of right line with the carrier-jaws of said pushers, and cause the passage of the sheet to the cutters in an oblique or angular position. If both gages remained in, they would exert great frictional resistance to the passage of the sheet. A further object of the alternate motion of the gage-plates as opposed to a simultaneous opposite movement of both is to prevent the "buckling up" and the subsequent springing back of the sheet which would take place should the sheet be slightly wider than the space between the gage-plates when both were in, and should they come together simultaneously and simultaneously separate, for, as will be readily understood, the sudden relief of such pressure exerted by the gage-plates as would cause the sheet to buckle will occasion the springing back of the sheet irregularly, so that when it resumes its rest upon the chute it will not be gaged thereupon. In the operation of my machine the hold-downs act to retain the sheet flat upon the chute after the gage-plates have acted to set the sheet in proper position upon the chute.

I have herein specified certain detailed mechanical arrangements, and have represented them in the drawings. I desire now to state that while I believe the mechanical contrivances referred to will enable the carrying out of my improvement into practical operation, I do not, however, intend to restrict myself to the precise forms represented, as I am well aware that many allied mechanical devices, when assembled in the relation and combination invented by me, will operate to effectuate in perhaps an equally-perfect manner the results which I first have obtained by the employment of the elements themselves. Thus, while it is of the gist of the invention that the pushers should be reciprocated lengthwise of the main chute, the gage-plates operated intermittently with respect thereto, the hold-downs alternately lifted and dropped, and the

stop-levers caused to rise and fall, it will be very obvious to a skillful mechanic that many mechanical devices other than those represented and described, but in all respects equivalent therefor, may be substituted in their stead and the operation referred to equally well effectuated. I therefore state that I lay little stress upon cam or lever-and-link constructions as such, and illustrate them merely as practical means well adapted to subserve the ultimate results in view.

Having thus described my invention, I claim and desire to secure by Letters Patent of the United States—

1. In an apparatus for trimming or shearing sheet metal, the following instrumentalities in combination, to wit: shearing mechanism adapted to cut a sheet of metal to a uniform width, a chute or table upon which the metal to be cut is placed or fed, and the reciprocating frame hereinbefore described, consisting of a sliding cross-head provided with a dovetail projection, and with pusher-carriers equipped with jaws and fitted to reciprocate lengthwise of the chute, substantially as described.

2. In an apparatus for trimming sheet metal, in combination with shearing mechanism adapted to cut a sheet of metal to a uniform width, a chute upon which the sheet of metal to be trimmed is placed or fed, a gate at or near the upper extremity of said chute, designed to control the introduction of the sheet upon the chute, stop-levers provided with upturned toes which pass through openings at or near the lower extremity of the chute and which control the discharge of the sheet to the shearing mechanism, and means for operating the stop-levers, so as to occasion the intermittent elevation and depression of the toes with respect to the carrying-surface of the chute, substantially as and for the purposes specified.

3. In a machine for trimming sheet metal, in combination with a main chute upon which the sheet of metal is fed and travels, the hold-downs hereinbefore described, a pushing-frame equipped with pushers, means for intermittently depressing said hold-downs against the face of the chute and for elevating them therefrom, and means for intermittently reciprocating the pushing-frame, substantially as and for the purposes specified.

4. In a machine for trimming sheet metal, the following instrumentalities in combination, to wit: a main chute upon which the sheet of metal to be trimmed is placed or fed, a pushing-frame for advancing the sheet into contact with shearing mechanism, shearing mechanism, two gage-plates at opposite sides of said chute, and mechanism for occasioning, first, the advance of one gage-plate; second, the advance of the other gage-plate; third, the retreat of said last-mentioned gage-plate, and, fourth, the retreat of the gage-plate first mentioned, substantially as and for the purposes specified.

5. In a machine for trimming sheet metal,

in combination with a feeding-chute, one or more stop-levers provided with upturned toes adapted to pass through apertures formed near the lower extremity of said chute, and 5 mechanism, substantially such as described, for alternately projecting said toes above the level of the carrying-face of said chute and retracting them beneath said level, substantially as and for the purposes set forth.

10. 6. In a machine for trimming sheet metal, in combination with mechanism for trimming the edges of a sheet of tin or other sheet metal, a primary chute adapted to receive the sheet to be trimmed, a gate for alternately closing 15 said primary chute and opening it to permit of the escape by gravity of the sheet placed thereupon, a main chute so relatively placed with respect to the primary chute as to receive the sheet as it descends from the latter, stop-levers provided with upturned toes for blocking the discharging end of said main chute, the hold-downs for retaining the sheet flat upon the main chute after its fall upon the latter, the pushing-frame for advancing the sheet of tin upon 20 the main chute, and means for operating said several instrumentalities, substantially in the manner hereinbefore set forth.

7. In a machine for trimming sheet metal, in combination with a chute upon which the 25 sheet to be trimmed is finally delivered, and from whence it is fed to the shearing mechanism, a pushing-frame adapted at predetermined intervals and by suitable means to force the sheet down the chute, stop-levers

provided with upturned toes likewise adapted 35 at predetermined intervals not correspondent with those at which the pushers are operated to either block the discharging end of said main chute or to leave it free for the passage of the sheet, and means for operating the pushers and the stop-levers, substantially as and for the purposes set forth.

8. In a machine for trimming sheet metal, the combination of a main chute, two gage-plates—one upon each side thereof—and means, 45 substantially such as is set forth, for occasioning, first, the advance of one gage-plate; second, the advance of the other gage-plate; third, the retreat of the last-mentioned gage-plate, and, fourth, the retreat of the gage-plate first mentioned, substantially as and for the purposes specified.

9. In a machine for trimming sheet metal, in combination with the main chute provided with a longitudinal way, a pusher-frame consisting of a sliding cross-head, a projection adapted to said way, and pusher-carriers equipped with jaws, substantially as set forth.

10. In a machine for trimming sheet metal, in combination with the main chute, the stop-levers provided with toes, the presser-feet, and the pushing-frame, substantially as set forth.

In testimony whereof I have hereunto signed my name this 2d day of November, A. D. 1882.

GEORGE H. PERKINS.

In presence of—

J. BONSALL TAYLOR,
JOHN JOLLEY, Jr.
